UNITED STATES PATENT OFFICE.

JESSE C. EAST, OF COLUMBUS, GEORGIA.

TRAVELING HINGE.

Application filed April 14, 1924. Serial No. 706,436.

To all whom it may concern:

Be it known that I, JESSE C. EAST, a citizen of the United States, residing at Columbus, in the county of Muscogee and State of Georgia, have invented certain new and useful Improvements in Traveling Hinges, of which the following is a specification.

This invention relates to traveling hinges, and is designed primarily for use upon show 10 and display case doors and has for its primary object the provision, in a manner as hereinafter set forth, of a traveling hinge of a construction whereby a traveling swinging movement may be imparted to the door 15 to which it is applied, to cause the door to move transversely of the face of the case and at the same time to swing inwardly therefrom to assume an open position at right angles to the face of the case and at 20 one side of the entrance thereto.

Another object of the invention is the provision, in a manner as hereinafter set forth, of a traveling hinge having wheeled track guided supporting means as a part of its 25 structure whereby an easier and smoother action may be obtained in shifting the door to which applied.

A final object of the invention is the provision in a manner as hereinafter set forth, 30 of a traveling hinge designed particularly for use upon showcase doors which will be of strong and durable construction, quiet and efficient in action, simple in construction, and inexpensive to manufacture and apply.

The invention will be best understood 35 from a consideration of the following detailed description taken in connection with the accompanying drawings forming part of this specification, with the understanding 40 that the invention is not confined to any strict conformity with the showing of the drawings, but may be changed and modified so long as such changes and modifications 45 mark no material departure from the salient features of the invention as expressed in the appended claims.

In the drawings:

Figure 1 is a vertical sectional view of a 50 case from the front to the rear thereof showing a door supported in open position upon a device of the character embodying this invention.

Figure 2 is a horizontal section taken upon the line 2—2 of Figure 1.

Figure 3 is a horizontal section taken upon the same line as Figure 2 but showing the

door of the case in closed position with the hinge structure at the front of the casing.

Figure 4 is an enlarged detail sectional view taken upon the line 4—4 of Figure 1. 60

Figure 5 is an enlarged detail sectional view taken upon the line 5—5 of Figure 1.

Figure 6 is an enlarged detail perspective view of the structure embodying this invention showing a portion of the door to which 65 it is applied.

Referring now to the drawings in detail wherein like reference characters indicate corresponding parts throughout the several views shown in the drawings a portion of 70 a showcase is shown having the usual top 1, base 2, back 3 and floor 4. The side wall 5 may be the outside wall or it may be the dividing wall for a double case. Along the side wall 5, the floor 4 is stepped down to 75 form the step 6 upon which the door carrying mechanism is supported. The front of the case is open as at 7 and this opening is adapted to be closed by the door 8 as shown in Figure 3. 80

Running from the front to the rear of the case upon the step 6 and also upon the under side of the top 1 above the step are parallel tracks 10 of T-shaped cross section secured in position by the screws 11 which are passed 85 through the cross heads of the members which form the flanges of the track. As will be clearly seen in Figure 1 these tracks 10 are in superposed relation one to the other.

The door 8 carries a pair of the hinges 90 embodying this invention, one at the upper side and the other at the lower, these hinges being in superposed relation, and except for the fact that the hinges are one upright and the other inverted, they are exactly alike in 95 structure and therefore the description of one only will be sufficient.

It is thought that a clearer understanding of the structure of the hinge will be had if attention is given to Figure 6 of the drawings. The hinge comprises a flat substantially elongated plate member 12 secured by means of bolts or screws 13 to the face of the door 8 adjacent the upper or lower edge thereof, depending, of course, upon whether 105 the hinge is applied to the top or the bottom of the door. Secured to the face of the plate 12, adjacent the inner end thereof, by means of rivets or other appropriate securing means 14, is one leaf 15 of a double 110 hinge member indicated as a whole by the numeral 16. This double hinge 16 com-

prises a substantially elongated flat central plate portion 17 having each end rolled as at 18 to provide hinge knuckles adapted to be pivotally connected to corresponding hinge knuckles 19 and 20 respectively of the aforementioned leaf 15 and a second leaf 21 connected to the other end of the plate 17. It will be noted that the plate 17 overhangs the outer end of the plate 12 and also the 10 side edge of the door 8 to which the two plates are connected. Therefore the leaf 21 swings upon the end of the intermediate portion 17, clear of the door 8. The free end of the outer hinge leaf 21 is bent at right 15 angles to the inner end, as at 22 so that the inner end of the leaf 21 when the plate 17 is lying flat against the plate 12, is at right angles to the plate 17 and the outer end 22 is parallel with the plate 17 and located at 20 a position back of it as is clearly apparent upon reference to Figures 2 and 6.

The angled extension 22 of the leaf 21 has the outer free portion provided with a series of vertically extending slots 23, the 25 purpose of which will become apparent, and the inner portion has secured thereto a threaded lug 23^a as shown.

Located beneath the plate 12 and the double hinge member 16 is an angled bar 30 of substantial length, one end of which is positioned beneath the plate and the hinge referred to, and the other end extending outwardly beyond the free end of the hinge. This angled bar has one flange 24 horizontally positioned with the outer face thereof opposing the under side of the door 8, and the other flange 25 has its outer face opposing the side of the lower portion of the side wall 5 and substantially parallel 40 with the inner face of the door 8; when the door is in open position, as will be clear upon reference to Figure 4 of the drawings.

The horizontal portion 24 of the angled bar has a pair of substantially elongated 45 slots formed therethrough and, longitudinally thereof as indicated at 26 and 27 respectively, the slot 26 being of slightly less width than the slot 27 and extending from the outer end of the angled bar to a point 50 adjacent the center thereof. The slot 27 has its inner end spaced from the inner end of the slot 26 and extends to a point adjacent the rear end of the angled bar.

Secured to the flange 24 of the angle 55 iron are three angle brackets 28, 29 and 30, the angle brackets 28 and 29 being supported at the outer end of the angled bar, the bracket 29 being located over the slot 26 and the bracket 28 being extended 60 through a slot in the side 25 and shiftably secured to the under side of the flange 24 of the angled bar, bolts 31 and 32 respectively, which pass through the slot 26 secure the brackets and are retained upon the under side by nuts 33 and 34.

The angle bracket 30 is in reverse position with respect to the position of the angle brackets 28 and 29, one arm thereof being positioned with its outer side adjacent the surface of the portion 24 above the slot 27 and carries a bolt 35 of substantial length, which extends through the slot and also through a roller 36 which is vertically positioned and adapted to travel in the slot 27. A nut 37 engages the lower end of the bolt 35 to secure the roller 36 in position in the slot 27 and against the under surface of the horizontal portion of the angle bracket 30. The vertical portion of the angle bracket 30 is countersunk in the inner 80 face of the door 8 and the plate 12 extends thereover and is secured thereto by rivets 38 as is clearly shown in Figure 4 of the drawings.

The vertical portion of the angle bracket 29 is secured to the rear face of the angled end 22 of the leaf 21, by means of screws 39 which extend through the slots 23 and engage in the vertical portion of the angle bracket 29. This angle bracket 29 further 90 has formed at the top thereof a forwardly extending finger 29^a having a threaded aperture therethrough and through this apertured finger there is extended a screw 29^b, the lower end of which engages in the lug 23^a to raise or lower the hinge and door to which it is connected. It may be seen here that the door may be raised or lowered by loosening the screws 39 and moving the angle bracket 29 to the desired position, by actuating the screw 29^b. This connection through the angle bracket 29, and screw, and the roller engaging in the slot 27 is the only connection between the portion 95 of the hinge secured to the door and the angled bar.

The vertical portion of the angle bracket 28 has passed therethrough a shaft 40. This shaft is fixed to the vertical portion of the bracket and carries upon its extended end at the outer side of the vertical portion of the bracket a roller 41, which roller has a peripheral groove 42 therein adapted to fit over the vertical portion of the track 10 to ride thereupon. A nut 43 engages the free end of the bolt 40 which forms a shaft for the wheel 41 and secures the wheel in position.

Located at the other or inner end of the angled bar against the face of the vertical portion 25 is a second wheel or roller 44 of smaller circumference than the wheel 41 and this wheel 44 is likewise peripherally grooved as at 45 to ride upon the track 10 engaged by the groove 42 of the other roller 41. A shaft 46 extends through the vertical portion 25 of the angled bar and through the center of the wheel 44 to support the same. A roller bearing 47 is located within the hub of the wheel 44 and surrounds 125

the shaft 46. The roller bearing is held in position, and the wheel is held upon the shaft 46 by means of a combined securing nut and gland element 48. This securing member 48 comprises a head having an annular peripherally threaded flange 49 which engages in the hub of the wheel and the roller bearing 47 is located within the annular flange 49 and held in position on the shaft 46 thereby. The outer end of the member 48 has a concentric threaded passage therethrough for engagement with the end of the shaft 46 to retain the wheel 44 thereon. Although the same has not been shown in the drawings it is desired that the bearing structure shown in conjunction with the roller 44 be also incorporated in the roller 41, in order that the action of the device may be noiseless and easy.

20 A roller member 50 is located upon the floor 4 adjacent the opening of the case and engages the inner face of the door 8 when the same is in closed position, as shown in Figure 3.

25 In action the swinging means embodying this invention operates as follows: Referring to Figure 1 of the drawings, where the door is shown in open position, when it is desired to close the door 8 of the case, 30 the same is moved toward the front and at the same time swung across the front of the case until the leading edge of the door abuts the jamb of the opening 7 upon the side of the case opposite the hinge. 35 This causes the rollers 41 and 44 to move along the track 10. At the same time that this forward movement is started the forward or preceding end of the doors is swung across the front of the case thus causing 40 the roller 36 to advance in the slot 27 of the angled bar, at the same time the leaves 15 and 21 of the double hinge 16 begin to swing at their respective ends of 45 the intermediate plate 17 and the rear end of the plate 12 moves away from the plate 17 and this action is continued until the roller 36 reaches the forward end of the slot 27 whereupon the door 8 will be positioned across the front of the case and the 50 central plate portion 17 of the double hinge 16 will assume a position across the angle formed between the door and the side of the case as is clearly shown in Figure 3.

55 In this position the plate 17 acts as a brace for the door 8 preventing it from being moved further. The roller 36 of course reaches the end of the slot and also prevents further swinging of the door. When this point is reached the roller 44 will have reached the forward end of the track 10 as indicated and the opening 7 will then be closed to prevent access to the interior of the case. Various adjustments may be made by means of the bolts 31 and 32 which may be loosened to shift the angled

bracket 28 or 29 in the slot 26 as desired. The door also may be raised or lowered as desired by loosening the bolts 39 which extend through the vertical slots 23 and actuating the screw 29.

Having thus described my invention what I claim is:

1. In a traveling hinge of the character described, a slotted roller supported element, a double hinge element comprising a central portion having a leaf pivoted to each end thereof, means carried by said supported element for connecting one of said leaves thereto, said other leaf being adapted for connection with a door, and guide means adapted to move in a slot of said element while in engagement with a door, to project said door at right angles to said slotted element when being moved to closed position.

2. In a traveling hinge of the character described, a roller supported element having longitudinally extending slots therein, a double hinge element positioned above said supported element and comprising a central portion having a leaf pivoted to each end thereof, one of said leaves being in connection with said supported element and the other adapted to engage with the face of a door, and guide means adapted to move in one of said slots while in engagement with a door to project said door at right angles to said slotted element while being moved to closed position.

3. In a traveling hinge of the character described, a roller supported element having longitudinally extending slots therein, a double hinge element positioned above said supported element and comprising a central portion having a leaf pivoted to each end thereof, one of said leaves being in connection with said supported element and the other adapted to engage with the face of a door, and guide means adapted to move in one of said slots while in engagement with a door, to project said door at right angles to said slotted element while being moved to closed position, said guide means being located beneath the door adjacent the rear thereof.

4. In a traveling hinge of the character described, a slotted roller supported element, a double hinge element comprising a central portion having a leaf pivoted to each end thereof, means carried by said supported element for connecting one of said leaves thereto, said other leaf being adapted for connection with a door, and guide means adapted to move in a slot of said element while in engagement with a door, to project said door to swing at right angles to said slotted element when being moved to closed position, said central portion of said hinge element being adapted to lie against the face of the door to which

attached, when the door is in open position, with one leaf extending freely beyond the rear of the door.

5. In a traveling hinge of the character described, a roller supported element having longitudinally extending slots therein, a double hinge element positioned above said supported element and comprising a central portion having a leaf pivoted to each end thereof, one of said leaves being in connection with said supported element and the other adapted to engage with the face of a door, and guide means adapted to move in one of said slots while in engagement with a door, to project said door at right angles to said slotted element while being moved to closed position, said central portion of said hinge element being adapted to lie against the face of the door to which attached, when the door is in open position, with one leaf extending freely beyond the rear of the door.

6. In a hinge for slidably and swingingly supporting a showcase door, a substantially elongated traveling element having longitudinal slots therein and further being partially extended longitudinally beneath said door when the same is in open position, a double hinge element comprising a central portion of substantial length having a leaf pivoted to each end, one leaf being secured to the face of said door and the other leaf normally freely extended beyond the rear thereof, means for connecting said freely extended leaf with said traveling element, and guide means connected with and depending beneath said door at the rear thereof and adapted to travel in one of said slots to project said door at right angles to said slotted element from said case when the same is moved to closed position.

7. In a hinge for slidably and swingingly supporting a showcase door, a substantially elongated traveling element having longitudinal slots therein and further being partially extended longitudinally beneath said door when the same is in open position, a double hinge element comprising a central portion of substantial length having a leaf pivoted to each end, one leaf being secured to the face of said door and the other leaf normally freely extended beyond the rear thereof, means for connecting said freely extended leaf with said traveling element, and guide means connected with and depending beneath said door at the rear thereof and adapted to travel in one of said slots to project said door at right angles to said slotted element from said case when the same is moved to closed position, said connecting means for said freely extended leaf having engaging means passing through another of said slots for adjustably securing the same to the traveling element.

8. In a hinge of the character set forth

for slidably and swingingly supporting a showcase door, a substantially elongated element having a pair of longitudinally extending slots therein, said element being partially extended longitudinally beneath said door when in open position, roller elements carried by said elongated element, hinge means pivotally secured at one end to the face of said door and having its other end extended beyond the rear of said door and in pivotal connection with said elongated element, and a roller guide member connected with and depending beneath said door at its rear and adapted to travel in one of said slots to project said door at right angles to said slotted element from said case when the same is swung to closed position.

9. In a hinge of the character set forth for slidably and swingingly supporting a showcase door, a substantially elongated element having a pair of longitudinally extending slots therein, said element being partially extended longitudinally beneath said door when in open position, roller elements carried by said elongated element, hinge means pivotally secured at one end to the face of said door and having its other end extended beyond the rear of said door and in pivotal connection with said elongated element, and a roller guide member connected with and depending beneath said door at its rear and adapted to travel in one of said slots to project said door at right angles to said slotted element from said case when the same is swung to closed position, one of said roller elements being capable of longitudinal adjustment upon said elongated element.

10. In a hinge of the character set forth for slidably and swingingly supporting a showcase door, a substantially elongated element having a pair of longitudinally extending slots therein, said element being partially extended longitudinally beneath said door when in open position, roller elements carried by said elongated element, an angle bracket having one portion resting upon said elongated element and having securing means extending therethrough and through one of said slots for adjustably securing the bracket upon the element, hinge means pivotally secured at one end to the face of said door and having its other end extending beyond the rear of said door and in pivotal connection with said angle bracket, and a roller guide element connected with and depending beneath said door at its rear and adapted to travel in one of said slots to project said door at right angles to said slotted element from said case when the door is swung to closed position.

In testimony whereof, I affix my signature hereto.

JESSE C. EAST.
